UNITED STATES PATENT OFFICE.

MICHAEL DOLIVO DOBROWOLSKY, OF WILMERSDORF, GERMANY, ASSIGNOR TO
GENERAL ELECTRIC COMPANY, A CORPORATION OF NEW YORK.

INSTRUMENT-TRANSFORMER.

1,098,664.

Specification of Letters Patent.

Patented June 2, 1914.

Application filed September 4, 1912. Serial No. 718,538.

To all whom it may concern:

Be it known that I, MICHAEL DOLIVO DOBROWOLSKY, a citizen of the Swiss Republic, residing at Wilmersdorf, Germany, have invented certain new and useful Improvements in Instrument-Transformers, of which the following is a specification.

My invention relates to instrument transformers and the object of my invention is to 10 protect such transformers against flux produced by adjacent conductors and of which no certain account can be taken in the design or calibration of the transformers or the instruments supplied thereby.

15 Current or series transformers have for a long time been used with both single and polyphase circuits for providing a comparatively small current for measuring and other purposes; the relations of the values 20 of the current supplied and the working current should be fixed. The current supplied by each secondary is of course proportional to the total flux in its iron core and this flux may be appreciably determined not 25 only by the current in the conductor which is surrounded by that core but also by the current in other conductors more or less remote according to the current strength in those other conductors. Thus where the 30 measurement is intended to be made directly from the current in one conductor only, the currents in other conductors of the same feeder may seriously affect the readings since the various conductors of a feeder are 35 normally laid as close to each other as possible. It is, therefore, ordinarily prescribed in what relation the conductors shall be laid. A simple way to prevent this undesired influencing to any appreciable extent is to lay 40 the conductors at a very great distance apart adjacent the points where the transformer or transformers are placed. This, however, is usually impossible or undesirable on account of lack of space and the phenomenon 45 of self induction.

My invention prevents the occurrence of any undesired influence by providing each conductor with a magnetic path, that is, a path of a paramagnetic material completely 50 closed or substantially so, surrounding the same. These magnetic frames surrounding the various conductors are arranged side by side in substantially the same plane and may be combined into one structure.

55 Figure 1 shows my invention applied to

two adjacent conductors. Fig. 2 shows a modification of the construction of Fig. 1. Fig. 3 shows my invention applied to a number of single-phase feeders, each having two conductors, or to a single feeder having a greater number of conductors. Figs. 4 and 60 5 show my invention applied to a plurality of conductors, which may be members of a polyphase feeder.

In Fig. 1 the conductors 1 and 2 are any 65 two adjacent conductors. They may be regarded as members of a single feeder supplying some distant point 2. About each of these conductors I have placed a magnetic path which, in this case, is completely 70 closed; each of these paths, all being in the same plane and all working below saturation, effectively prevents flux from its conductor from entering another path. These paths I have here combined into a single 75 magnetic frame 4; the secondary winding 5 which supplies the instruments has been located on the common leg 6. As will be understood, the flux produced by both of the mains under these conditions will influence 80 the instrument and the instrument will therefore, be calibrated or designed with this in mind. This construction is particularly adapted to the condition that the two conductors are members of the same feeder. 85 However, there can be no stray and uncalculable flux from either conductor influencing the secondary winding 5, as would be the case were the iron path about one of the mains omitted. The location of the secondary 90 winding about a part of the iron paths which convey flux induced by both mains is obviously not a necessary feature; the location of the secondary on the core must be taken into account during the design or calibration of the devices to be supplied in any 95 case.

In the modification of the construction shown in Fig. 1, which I have illustrated in Fig. 2, an ordinary instrument transformer 100 4' is located about the conductor 1'. About any other conductor 2' which it is feared may influence the transformer 4' is located the frame 4'' providing a magnetic path for the flux from the conductor 2'. This frame 105 4'' is located in substantially the same plane as the core 4' and therefore shields the core 4' from flux from the conductor 2'. The secondary 5' may be located wherever desired on the core 4'. 110

Wherever it is desired to measure the combined energy flowing through a plurality of single phase feeders, a single path may be disposed about all similar conductors of the various feeders, as is shown in Fig. 3. 5 Here again all the paths are combined into a single frame. In this figure, the mains 1 and 2 are members of one of the feeders, the mains 1' and 2', and 1'' and 2'', being members of two other feeders respectively. 10 The secondary winding has again been placed about the common leg of the core. In this instance I have shown the secondary winding 7 as divided into two parts, each 15 part being located between two feeders. In this case also, it will be apparent that there can be no unaccounted for flux through the iron core and the secondary winding from any of the members of these feeders, providing of course that the feeders are not bent back upon themselves in the neighborhood of the core. This would be an unusual 20 condition and might be accounted for by a further application of my invention. 25 Figs. 4 and 5 illustrate different constructions involving my invention, both designed to accomplish the results desired with poly-phase systems. It will be seen that each of the mains 10, 11 and 12 is surrounded by an iron path which again is a part of a single 30 frame 13. The iron path about each feeder shields from undesired flux from that feeder the iron path in substantially the same plane about every other feeder. Fig. 4 has been 35 designed to accommodate as many secondary windings as there are mains; Fig. 5 produces the same results while using one less winding than there are mains. The meter

connections to the secondary windings are well understood.

What I claim as new and desire to secure by Letters Patent of the United States, is:—

1. The combination with a plurality of conductors, of a series transformer connected to one of said conductors, and a substantially closed path of paramagnetic material surrounding each of the remaining conductors and lying in substantially the same plane as the core of the transformer.

2. The combination with a plurality of conductors, of a series transforming device having a substantially closed magnetic path surrounding each of said conductors and a secondary winding surrounding portions of said paths carrying flux induced therein by a plurality of said conductors.

3. The combination with a plurality of conductors, of a series transformer having a substantially closed magnetic path surrounding each of said conductors, all the paths lying in substantially the same plane, and a secondary winding surrounding portions of said paths carrying flux induced therein by a plurality of said conductors.

4. The combination with a plurality of conductors, of a series transformer comprising a magnetic frame providing a substantially closed path surrounding each conductor and a secondary winding thereon.

In witness whereof, I have hereunto set my hand this 7th day of August, 1912.

MICHAEL DOLIVO DOBROWOLSKY.
